(57) **CLAIM**

I claim the ornamental design for a coupler fitting for an
artificial tree segment, as shown and described.

DESCRIPTION

FIG. 1 is a bottom perspective view of a coupler fitting for an
artificial tree segment showing my new design;

FIG. 2 is a top perspective view thereof;

FIG. 3 is a side elevation view thereof;

FIG. 4 is a top view thereof;

FIG. 5 is a bottom view thereof; and,

FIG. 6 is a cross sectional side view taken along line 6—6 in
FIG. 5.
